US00D701169S

(12) **United States Design Patent**
Brown

(10) **Patent No.:** **US D701,169 S**
(45) **Date of Patent:** **** Mar. 18, 2014**

(54) **RECONFIGURABLE PLUG ADAPTER**

(75) Inventor: **Gareth Brown**, Jersey City, NJ (US)

(73) Assignee: **Quirky, Inc.**, New York, NY (US)

(**) Term: **14 Years**

(21) Appl. No.: **29/397,199**

(22) Filed: **Jul. 13, 2011**

(51) LOC (10) Cl. **13-03**

(52) U.S. Cl.

USPC **D13/137.1**

(58) **Field of Classification Search**

(57) **CLAIM**

The ornamental design for a reconfigurable plug adapter, as shown and described.

DESCRIPTION

FIG. 1 is a front perspective view of a first embodiment of a reconfigurable plug adapter;

FIG. 2 is a back perspective view thereof;

FIG. 3 is a top view thereof;

FIG. 4 is a bottom view thereof;

FIG. 5 is front view thereof;

FIG. 6 is a back view thereof;

FIG. 7 is a left side view thereof;

FIG. 8 is a right side view thereof;

FIG. 9 is a front perspective view of a second embodiment of a reconfigurable plug adapter;

FIG. 10 is a back perspective view thereof;

FIG. 11 is a top view thereof;

FIG. 12 is a bottom view thereof;

FIG. 13 is front view thereof;

FIG. 14 is a back view thereof;

FIG. 15 is a left side view thereof; and,

FIG. 16 is a right side view thereof.

The broken lines immediately adjacent the shaded areas represent the bounds of the claimed design while all other broken lines are directed to environment and are for illustrative purposes only; the broken lines form no part of the claimed design.

1 Claim, 16 Drawing Sheets
